(57) **CLAIM**

The ornamental design for an eyelash curler, as shown and described.

DESCRIPTION

FIG. 1 is a front and top perspective view of an eyelash curler, showing our new design;
FIG. 2 is a rear and bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof; and,
FIG. 9 is an enlarged perspective view of the eyelash curler shown within the area designated as 9 in FIG. 1.
The dashed lines in the figures illustrate portions of the eyelash curler that form no part of the claimed design. The dash dot dash lines in FIGS. 1 and 9 are for the purpose of illustrating the enlarged view indicators and form no part of the claimed design.

1 Claim, 9 Drawing Sheets
